UNITED STATES PATENT OFFICE.

CHARLES M. HEETER, OF BUTLER, PENNSYLVANIA.

OIL-WELL PACKER.

1,422,704.

Specification of Letters Patent. Patented July 11, 1922.

Application filed September 26, 1918. Serial No. 255,765.

To all whom it may concern:

Be it known that I, CHARLES M. HEETER, a citizen of the United States, residing at Butler, in the county of Butler and State of Pennsylvania, have invented a new and useful Improvement in Oil-Well Packers, of which the following is a full, clear, and exact description, reference being had to the accompanying drawings, forming part of this specification, in which—

Figure 1 is a longitudinal sectional view through one form of packer comprising my invention, and

Figure 2 is a similar view showing the packer in position.

This invention relates to an improvement in packers and is designed to provide an inexpensive and efficient device whereby the packer can be rapidly removed from the well when it is desired to withdraw the same.

Heretofore in packers of this character it was frequently a difficult job to withdraw the packers as it was necessary to withdraw the packer in its entirety.

The object of my invention is to provide a device of this character which can readily be withdrawn in sections. The precise nature of my invention will be best understood by reference to the accompanying drawings which will now be described, it being premised, however, that various changes may be made in the details of construction and arrangement of the parts without departing from the spirit and scope of my invention as defined in the appended claims.

In Figures 1 and 2 I have shown my invention applied to what is known to the trade as an anchor packer, wherein the reference character 2 designates a casing member of the packer. Connected to the lower end of this casing member 2 is a pipe 3, which extends from the casing member 2 to the bottom of the well, and forms the support for the packer. Slidably mounted within the casing member 2 is a tube 4, which extends through and is arranged to move with relation to a flexible packing member 5, which packing member may be made of rubber or any suitable material. This packing member normally rests upon a flanged member 6 connected to the upper end of the casing 2 through which the tube 4 is adapted to slide, and which forms a support for the packing member during the setting thereof. Connected to the lower end of the tube 4 by means of frangible pins 7, is a ring or

bushing 8, which is also arranged to slide with relation to the casing member 2. Connected to the tube 4 is a packing expander 9, which is above the packing member when the packer is lowered into the well as shown in Figure 1. 10 is a packing compressor connected to the tube 4 above the packing expander 9; and connected to this compressor is a pipe 11 for the oil, which leads to the top of the well. If desired the expander 9 may be omitted and in which case the packing member 5 is compressed and expanded by the compressor 10.

When the packer, together with the tubing connected thereto, is lowered into the well the parts are in the position shown in Figure 1 and in which the packer, as well as the tubing extending downwardly from the packer, are supported by the bushing 8, the length of the pipe or tubing 3 being such that when the lower end thereof engages the bottom of the well, the packer will be in the position in which it is to be set. When the lower end of the tube or pipe 3 engages the bottom of the well, the tube 4, together with the pipe 11, will move downwardly with relation to the packing member 5 and the casing 2, and when moving downwardly the expander 9 will expand the packing 5 against the wall of the well and if the weight of the tube is sufficient, the upper portion of the packing 5 will be pressed downwardly by the compressor 10 into engagement with the wall of the well. When the parts have been moved to this position, the bushing 8 has been moved downwardly with relation to the flanged member 6, as clearly shown in Figure 2.

When it is desired to remove the packer, the pipe 11 is drawn upwardly and with it the tube 4 and the expander 9, and if the packing should stick about the wall of the well, the pins 7 will be sheared when the bushing 8 contacts with the flanged member 6, so that the tube 4 will be withdrawn from the packing member 5. The packing member 5 can then readily be removed by means of fishing tools and after the packing member 5 has been removed, the casing member 2, together with the pipe 3 connected thereto, can also be removed by means of the usual fishing tools.

The advantages of my invention result from the provision of a packer having frangible connections which are arranged to be broken and to permit the packer to be re-

moved in sections, in case the packing sticks, but which will remove the packer as an entity if the packing does not stick.

I claim:

- 5 1. A well packer, comprising a casing, a tube telescopically mounted with respect to said casing, a flexible packing member surrounding said tube, flanged means detachably secured to said casing for supporting the lower end of said packing member, said flanged means being disconnected from said tube to permit movement of the tube therethrough, expanding means on said tube for expanding said packing member when the 15 tube is moved through said flanged member into the casing, and a frangible connection between said tube and said casing permitting the tube to be removed without removing the packing member in case the packing 20 should stick, but permitting removal of the packer as a unit in case the parts thereof do not stick, substantially as described.

- 25 2. A well packer, comprising a casing, a tube telescopically mounted with respect to said casing, a flexible packing member surrounding said tube, flanged means detachably secured to said casing for supporting the lower end of said packing member and forming a guide for said tube, expanding 30 means on said tube for expanding said packing member when the tube is moved into the casing, a ring surrounding the lower end of said tube, and a frangible connection between said tube and said ring permitting

the tube to be removed without removing the packing member and ring in case the packing should stick, but insuring removal of the packer as a unit if the parts do not stick, substantially as described.

3. A well packer, comprising a casing, a tube telescopically mounted with respect to said casing, a flexible packing member surrounding said tube, and supported at its lower end by said casing, expanding means on said tube for expanding said packing member when the tube is moved into the casing, a bushing on the lower end of said tube freely movable relatively to said casing and adapted to guide said tube within the casing, and a frangible connection between said tube and said bushing permitting the tube to be removed without removing the packing member in case the packing should stick, but permitting removal of the packer as a unit if the parts do not stick, substantially as described.

4. A well packer, comprising a support, a tube, a packing member, means to expand said packing member when the packer is set, and means operatively connecting said tube and packing member to simultaneously remove the same if the packing does not stick and to permit the tube to be independently removed in case the packing does stick, substantially as described.

In testimony whereof, I have hereunto set my hand.

CHARLES M. HEETER.
